UNITED STATES PATENT OFFICE.

GEORGE WILSON SHACKLETON, OF KEIGHLEY, ENGLAND, ASSIGNOR TO GEORGE HATTERSLEY AND SONS LIMITED, OF KEIGHLEY, ENGLAND.

WEFT STOP MECHANISM FOR LOOMS.

Application filed March 28, 1927, Serial No. 178,940, and in Great Britain March 26, 1926.

This invention relates to improvements on the weft-stop mechanism for looms for which Letters Patent No. 1,238,947 were granted in the United States on September 4th, 1917. 5 By the mechanism of that patent, when the weft fork or detector indicates a broken or failing pick of weft, the picking mechanism is disengaged or arrested, the pattern surface mechanism has its direction of motion reversed while the loom runs forward for two picks or revolutions of the crank shaft. The direction of motion of the pattern surface is then readjusted into its proper operating direction and the loom proceeds forward for another pick or for one revolution of the crank and then the whole mechanism of the loom comes to rest with the shed of warp in its proper order to receive the repaired shot of weft. 10 15 20 25

In connection with broad looms it is usual to make use of two detectors one for engaging the weft in one half of the width of the fabric and the other in the other half, each or either of which detectors will effect a stoppage when the weft is absent.

It often happens that when the weaver repairs the broken or failing part of the weft under the conditions stated, the newly inserted portion of the weft does not lie in 30 the path of one or other of the weft forks or detectors, consequently when the weaver restarts the loom into motion the weft fork or detector in performing its usual detector movements fails to find any weft in its path and therefore immediately indicates the absence of the weft with the result that the 35 picking is again suspended and the pattern surface reversed and caused to repeat all the previously performed functions above explained.

In order that my said invention may be readily understood, I have hereunto appended sheets of drawings illustrative thereof, to which by letters and figures reference is made in the following description in which:—

Fig. 1 is a sectional end elevation of sufficient of a loom to illustrate the application of my improved parts. 50 Fig. 2 is a view of the parts shown by Fig. 1 as seen looking from left to right of said figure. Fig. 3 is a sectional front elevation of the breast rail of the loom with my improved parts fixed thereon.

Fig. 4 is a plan of the parts shown by Fig. 3 but with the breast rail omitted.

Fig. 5 is a sectional elevation of the parts shown by Fig. 3 looking from right to left of said figure. 60

Fig. 6 is a sectional end elevation similar to Fig. 5 but shows parts to the rear of those shown by said figure.

Fig. 7 is a plan of certain of the parts shown by Fig. 6. 65

Fig. 8 is a similar view to Fig. 6 but shows parts in altered positions as hereinafter explained.

Fig. 9 is a plan of the parts shown by Fig. 8.

Figs. 10 and 11 are similar views to Figs. 70 8 and 9 respectively but show the parts in other altered positions.

Fig. 12 is a similar view to Fig. 3 but shows only one of the levers and the part which has moved it into another position. 75

Figs. 3 to 12 inclusive are drawn to an enlarged scale as compared with Figs. 1 and 2.

A indicates the end frame of the loom, B the slay-board or lay, C the breast or front rail and E one of the loom's driving shafts. 80

To attain the object of my invention I make use of the apparatus and devices described in my prior patent (No. 1,238,947) and although certain of the parts herein shown and described are of modified form 85 and arrangement yet the functions of the whole are of the character set forth in the said patent. Therefore, so far as is possible the letters and figures of reference which I make use of hereinafter will apply to the members or parts referred to by corresponding letters and figures in the said patent.

In connection with the devices above referred to I now make use of a modified arrangement and construction of bunter mechanism which I arrange to be actuated by any well known weft detector or weft fork devices which control the movements of the usual dagger member *a* carried by the slay-board B, said movements being in a horizontal path in a direction lengthwise the said slayboard B as is well known. 95

In my present bunter mechanism I make use of two sliding bars *b* and *b*^o, the bar *b* being the primary one which brings into action all the devices which carry out the functions hereinbefore described, while the bar *b*^o controls the engaging of the said bar *b* with the parts its actuates as is herein-after described. 105 110

These bunter bars b and b^e are mounted to slide upon their supporting bracket 12 which is fixed upon the rail C, and are arranged to occupy positions adjacent each other as is shown by the drawings, more particularly Figs. 7, 9 and 11, and they are arranged to occupy their normal advanced positions as shown by Figs. 4 and 5, by the actions of the open spiral springs b^7 , b^8 (shown in broken lines Figs. 3 and 5) which are respectively embedded in them, taking against the bracket 12.

Above these bars b , b^e is a double acting catch 13 which is pivoted at 13^b upon a lever 14, in such a manner that its outer catch part 13^a may rest upon the bars b and b^e and engage with them as is herein-after explained.

The lever 14 has the connecting rod c pivoted to it so that this rod c may reach down to actuate the retaining catch d^5 to bring about the actions fully described in the prior Patent 1,238,947.

The normal position of the lever 14 is secured by its outer end 14^a bearing against the rail C as is shown by Figs. 1, 5, 6 and 8.

During the ordinary weaving operations of the loom the dagger a is carried by the slayboard B in a path in which the supplementary bunter bar b^e is situated. Consequently at its first advancing movement it will move bar b^e forward to its position shown by Figs. 8, 9, 10 and 11, and by doing so it will have moved the upwardly extending projection b^9 on the bar b^e , from beneath the catch part 13^a on the catch 13. When the loom is in motion, the rod 15 (which acts in conjunction with the starting rod or handle 16 carried by the lever 17) is in the position shown by Fig. 12 and when the bar b^e has been thus moved, the catch 13 may descend so that its part 13^a will engage with and retain the bar b^e in the position shown by Figs. 8, 9, 10 and 11, and at the same time be positioned in the path of the projection b^{10} on the bar b . When the loom is at rest or out of action the hoop 18 fixed upon the said rod 15 engages the upper end of the lever 19 and moves the lower arm 19^a of said lever to cause same to engage with the flange 13^a on the catch 13 to raise said catch out of contact with both of the bars b and b^e . When the rod 15 is moved to start the loom to carry out the weaving operations, the rod 15 occupies a position where the hoop 18 fixed upon it, is out of contact with the lever 19 while the hoop 18^a (also fixed upon said rod 15) is caused to move said lever 19, so that its arm 19^a will fail to support the catch 13 as is shown by Fig. 12.

From the foregoing description it will be observed that whenever the loom is started, the two bunters b and b^e will both be occupying their normal advanced positions

shown by Figs. 4, 5, 6 and 7 into which positions they will have been brought by the action of their springs b^7 , b^8 which had previously been released by the sliding of the rod 15 (when the loom was stopped or had its motion arrested) causing the lever 19 to raise the catch 13.

With the two bunters b and b^e in their forward positions as stated, should there be no weft to arrest the descent of the weft fork or detector, the dagger a will be slid into its position opposite the primary bunter b and by the advancing movement of the slayboard B it will strike said bunter b and cause it to slide under the part 13^a of the catch 13 which at this time will be held above and clear of same, so that its projecting part b^{10} will not engage with the part 13^a , hence this forward movement of the bunter b and its return movement will be idle or non-effective.

On the other hand when the two bunters b and b^e occupy their forward positions and there is a shot of weft present beneath the weft fork or detector, then the dagger a will be adjusted by such weft in a position opposite the bunter b^e so that by its advancing movement with the slayboard, it will strike or engage said bunter b^e and will carry same with it to cause the projection b^9 to go beyond the part 13^a of the catch 13 hence this will fall and will be engaged between the projection b^9 and the edge of the projection b^{10} on the bunter b .

In both of said cases the crank shaft of the loom will have revolved through one revolution (or for one pick) without acting upon any part which, under the conditions and for the reasons stated, could start the mechanism into action for effecting the disengagement of the picking, the reversing of the pattern surface mechanism and other devices hereinbefore referred to. Consequently the disadvantages heretofore met with are avoided, and the loom continues in motion for effectively performing its weaving functions with the two bunters adjusted in their respective positions shown by Figs. 8, 9, 10 and 11. The said positions are maintained by said bunters until another broken or failing shot of weft occurs. This failure will result in the descent of the weft fork or detector which will move the dagger a into position opposite the bunter b and the engagement of the projection b^{10} thereon with the catch 13 will move lever 14 and its connecting rod c , to place the whole mechanism into action to repeat the functions hereinbefore explained.

Such being the nature and object of my said invention what I claim is:—

1. In a loom of the character described, the combination with control mechanism and a weft detector including a member movable with the lay, of a bunter comprising two

sliding bars, one of said bars being positioned in the path of the weft detector member on the lay when the weft is in proper condition and the other of said bars being in the path of movement of said detector member when the weft is broken, springs for moving both said bars in a direction opposite that in which they are moved by said weft detector member, a catch adapted to connect said bars when the first said bar has been moved by the weft detector member in opposition to its coacting spring, and connections between said catch and the control mechanism, for the purpose described.

2. In a loom of the character described, the combination with control mechanism and a weft detector including a member movable with the lay, of a bunter comprising two sliding bars, one of said bars being positioned in the path of the weft detector member on the lay when the weft is in proper condition and the other of said bars being in the path of movement of said detector member when the weft is broken, a catch adapted to retain the first said bar in the position to which it is shifted by the weft detector member and to connect the two bars, a lever supporting said catch, and a rod connecting said lever with the control mechanism, for the purpose described.

3. In a loom of the character described, the combination with control mechanism and a weft detector including a member movable with the lay, of a bunter comprising two sliding bars, one of said bars being positioned in the path of the weft detector member on the lay when the weft is in proper

condition and the other of said bars being in the path of movement of said detector member when the weft is broken, each of said bars being provided with an upward projection, springs for moving both said bars in a direction opposite that in which they are moved by said weft detector member, a catch adapted to be positioned between said projections on said bars and connect them when the first said bar is shifted by the weft detector member, and means to transmit movement of said connected bars to the control mechanism, for the purpose described.

4. In a loom of the character described, the combination with control mechanism and a weft detector including a member movable with the lay, of a bunter comprising two sliding bars, one of said bars being positioned in the path of the weft detector member on the lay when the weft is in proper condition and the other of said bars being in the path of movement of said detector member when the weft is broken, each said bars being provided with an upward projection, springs for moving both said bars in a direction opposite that in which they are moved by said weft detector member, a catch adapted to be positioned between said projections on said bars when the first said bar is shifted by the weft detector member, means for retaining said catch in elevated position above both said bars when the loom is idle, and means connecting said catch and control mechanism, for the purpose described.

GEORGE WILSON SHACKLETON.
